CROSSED FIELD HIGH FREQUENCY ELECTRON
DISCHARGE APPARATUSRonald L. Bell, Woodside, and Gordon S. King and Joseph
K. Maau, Palo Alto, Calif., assignors to Varian Asso-
ciates, Palo Alto, Calif., a corporation of CaliforniaFiled July 3, 1961, Ser. No. 121,378
18 Claims. (Cl. 315—39.3)

This invention relates to high frequency electron discharge apparatus, and, more particularly, to high frequency apparatus employing a "crossed-field" that comprises an electrostatic field disposed perpendicular to a magnetic field.

When the size of a radio frequency (R.F.) apparatus such as an electron discharge device operating in the kilomegacycle per second range is scaled down so that the apparatus will operate at still higher frequencies, the power output of the tube falls off, the parts become overheated, and some of the parts are so small that they cannot be readily fabricated. These conditions are also true when the size of a "cross-field" R.F. apparatus is scaled down to operate at higher frequencies since, for example, the spacing between the negative sole electrode and the positive slow-wave electrode must be made proportionately smaller than in lower frequency tubes, making the problem of voltage breakdown acute. Also, high beam currents cannot be achieved because the effective cathode area will diminish rapidly as the frequency increases since the effective cathode length, traditionally a function of wavelength, decreases. At the same time, the efficiency of the tube falls off due to the decreased beam current driving a decreasing circuit impedance. The increased space charge density in the electron beam necessary to produce high powers in a smaller tube combines with the above effects to depreciate the over-all tube performance quite severely.

There are also fabrication difficulties inherent in reproducing the fine mechanical detail required in tubes that must operate well over 10,000 megacycles per second. Thus, new methods for generating electron beams must be found which ease the problem of cathodes loading in existing scaled down guns of the conventional design wherein the length is a function of wavelength. Also, a new slow-wave circuit must be utilized which provides a wide interaction space so that higher beam currents can interact with the R.F. waves traveling on the slow-wave circuit without requiring an increase in space charge density of the beam.

Most of the problems which are encountered when one tries to increase the operating frequency of an electron tube are also encountered when one tries to increase the power output of tubes without increasing the operating frequency, such as the problem of more efficient cooling and the problem of voltage breakdown.

The principal object of this invention is to produce a cross-field tube with higher efficiencies and higher output power, especially when the operating frequency is increased.

One feature of this invention is an electron gun having an emitting surface disposed parallel to the electron beam with the length of the emitting surface in the direction of the beam greater than the length between the points of origin of a cycloidal period followed by any electron.

Another feature of this invention is an electron gun wherein the electrons are accelerated into a non-uniform electric field so that electrons emitted at one end of the gun are not recaptured at the other end of the gun.

Another feature of this invention is a "gradient cathode" wherein the potential varies uniformly from end to end of the cathode.

2

Another feature of this invention is an electron gun wherein the electrons are accelerated into an increasing electric field.

Another feature of this invention is a slow-wave structure having tapered fingers to increase strength and cooling rate.

Another feature of this invention is an improved structure for maintaining dimensional tolerances at all operating temperatures.

Another feature of this invention is an improved sole to retain the electron beam dense and close to the slow-wave structure.

Another feature of this invention is an improved collector for collecting a high density beam within a very small space.

These and other objects and advantages will become apparent upon a perusal of the following specification taken in connection with the accompanying drawings wherein:

FIG. 1 is a longitudinal cross-sectional view of a typical cross-field tube employing the features of this invention,

FIG. 2 is a cross-sectional view taken on line 2—2 of FIG. 1 in the direction of the arrows,

FIG. 3 is a cross-sectional view taken on line 3—3 of FIG. 1 in the direction of the arrows,

FIG. 4 is a cross-sectional view taken on line 4—4 of FIG. 1 in the direction of the arrows,

FIG. 5 is a view taken on line 5—5 of FIG. 1 in the direction of the arrows,

FIG. 6 is an enlarged detail view of the region housing the electron gun shown in FIG. 1,

FIG. 7 is a cross-sectional view taken on line 7—7 of FIG. 6 in the direction of the arrows,

FIG. 8 is a view of the slow-wave structure taken on line 8—8 of FIG. 1 in the direction of the arrows,

FIG. 9 is an alternate embodiment for the electron gun shown in FIG. 6;

FIG. 10 is a view taken on line 10—10 of FIG. 9 in the direction of the arrows,

FIG. 11 illustrates the equipotential lines for the cathode surface in FIG. 9 and trajectories of electrons leaving the cathode, and

FIG. 12 is an enlarged view of the interdigital line forming the slow-wave structure of the tube shown in FIG. 1.

Although the tube illustrated is a backward-wave oscillator employing a crossed-field, the teachings of this invention may be used in an amplifier.

Referring to the drawings and to FIGS. 1 and 2 in particular, the crossed-field tube embodying the present invention has a rectangular envelope 12 with magnetic pole pieces 13 and 14 disposed in opposite side walls 16 and 17, respectively, of the envelope. The envelope has a pinched-off exhaust tubulation 18 and two waveguides 19 and 21 protruding therefrom. Ceramic windows 22 and 23 are each sealed at their periphery by suitable vacuum tight seals 24 to the interior walls of the waveguides 19 and 21, respectively, and within the envelope the waveguides are connected to a slow-wave circuit 26 in a manner as will be more fully described hereinafter.

An electron gun assembly 27 and a collector assembly 28 are positioned at opposite ends of the envelope 12 with the slow-wave circuit 26 and a sole electrode 29 positioned therebetween. These elements are disposed between the two pole pieces 13 and 14 and within a magnetic field that may be formed by a permanent horseshoe magnet or an electromagnet (not shown) fixed to the pole pieces 13 and 14. Extending from the envelope 12 adjacent the electron gun assembly 27 is an assembly 31 comprising an alternate stack of metal and ceramic rings, metal ring 32 serving as a terminal for an anode 33 of the gun assembly 27 and metal rings 34 and 36 serving as terminals for a cathode heater 37 (more clearly

shown in FIGS. 6 and 7) which is positioned within a cathode holder 38 which serves to support a cathode emitter 39. A metal ring 41 (FIG. 1) serves as the terminal for the cathode 39, while the terminal for the sole 29 is a cup-shape member 42 closing the end of the assembly 31.

The electrodes which make up the gun assembly 27, the sole 29, and the collector assembly 28 are mounted on a ceramic bar 43 (shown in detail in FIG. 4) which is mounted on the side wall 16 parallel to the face of the pole piece 13. The ceramic bar 43 has at least three accurately located grooves in the surface thereof facing the interior of the tube. These grooves include a horizontal groove 44 running the length of the bar 43 and parallel to and at a predetermined distance from a top edge 45 thereof and two accurately spaced grooves 46 and 47 (FIG. 6) aligned perpendicular to the groove 44 and at the cathode end of the tube. The anode 33 has accurately spaced lugs 49 and 49' (FIG. 5) which mate with the groove 44 and lug 49'' which mates with groove 46 on the bar 43 accurately locating the anode with respect to the bar. A bolt 50, suitably insulated, screws into the side wall 16 to hold the anode in place. The cathode holder 38 has lugs 51 and 51' which mate with the grooves 47 and 44, respectively, in the ceramic bar 43 to accurately locate the cathode. A ceramic cathode enclosure 52 mates with pins 38' (FIG. 6) on the cathode holder 38 and holds the cathode holder 38 against the ceramic bar 43 electrically insulated from the other parts in the tube. The cathode enclosure 52 is held in place by a spring strap 53 (FIG. 5) extending from the bolt 50. A surface 54 (FIGS. 6 and 7) on the anode is preferably inclined at a slight angle to the direction of the beam and faces an emitting surface 55 on the cathode 39 to form a wedge-shape chamber therebetween. By means of the terminals 32 and 41 and a power source, not shown, the anode is maintained at a positive potential with respect to the potential on the cathode. The strength of the electric field created by this potential difference is greater between the surfaces 54 and 55 near the sole 29 where the surfaces are closest to each other. The direction of the magnetic field created between pole pieces 13 and 14 is oriented such that the electrons emitted from the cathode 39 follow a cycloidal path in the direction of increasing electric field and towards the sole 29. The electrons emitted from the cathode surface 55 in the weaker electric field follow a longer cycloidal period than the electrons emitted from surface 55 in the stronger electric field. A period is the length between identical points of the cusps of a cycloid. Thus, the surfaces 54 and 55 can be so arranged to provide an electrical field which causes all the emitted electrons to have cycloidal periods of different length which all crest at the same plane normal to the beam or have their velocity vector substantially parallel to the beam at this plane. The electrons are then extracted from the gun region to form an electron beam. An electron beam having a much higher density than in the prior art is produced since the length of the cathode emitting surface 55 aligned with the beam need not be limited to less than the length of the smallest cycloidal period to prevent cathode recapture of electrons by the cathode. The electron gun of this invention causes the electrons emitted furthest from the slow-wave structure to form longer cycloid periods so that they will not be recaptured by the cathode. Since the beam is at a relatively high density, the cathode holder 38 has upwardly protruding non-emitting ridges 56 (side hats) which extend towards the anode surface 54 to prevent the electrons from traveling sideways in the direction of the magnetic field. This arrangement of anode and cathode surface to form a tapered chamber is also useful in low density beams and short length cathode since almost all the electrons in the beam are traveling in a direction parallel to one another after they leave the gun.

The electrons of the beam can be accelerated to higher

energies as they enter the elongated space between the sole 29 and the slow-wave structure 26 or the electrons can enter this space having the same energy as in the gun assembly 27. In this embodiment, the electrons are further accelerated by tapering the space between the sole 29 and the slow-wave circuit 26 so that the electrons move into an increasing electric field formed by sloping surfaces 57 (FIG. 6) on the negatively biased sole and sloping surface 57' on a grounded electrode 58 that is provided between the end of the anode 33 and the slow-wave circuit 26 to shape the electrostatic field in the region between the gun assembly 27 and the slow-wave circuit 26.

The surface of the sole 29 (FIG. 4) facing the slow-wave structure is formed with protruding fins 59 over the entire length thereof and disposed parallel to the beam to reduce secondary electron emission. Protruding side hats 60 on the side edges of the sole 29 are disposed directly opposite an interdigital line 61 formed in the slow-wave circuit 26, the side hats preventing the beam from spreading so that optimum R.F. field-beam interaction is obtained.

The support structure between the sole 29 and the slow-wave circuit 26 minimizes the effects of the different thermal expansion coefficients of the tube parts in the following manner: the sole 29 has a laterally protruding ridge 62 which has a surface 63 that faces in the same direction as the face of the sole formed by fins 59 and is accurately positioned parallel to the face of the sole. The ridge 62 engages the horizontal groove 44 in the ceramic bar 43 for accurately positioning the sole 29 with respect to the bar 43. Bolts 64, suitably insulated, screw into the side wall 16 and retain the sole in place. As pointed out above, the top edge surface 47 of the bar 43, being accurately spaced from grooves 44 and parallel thereto, engages the slow-wave circuit 26 at a ledge 67 that is accurately spaced from the interdigital line 61. The surface 45 of the ceramic bar 43 is urged against the ledge 67 and the ridge 62 on the sole is urged against the side of the groove 44 by a plurality of spring clips 68 acting on ceramic wedges 69 positioned under the sole 29. Suitable bolts 71 retain the spring clips 68 in place. This arrangement of parts allows the dissimilar materials of the components to thermally expand without appreciably affecting the spacing between the sole 29 and the interdigital line 61 since the reference portions 45 and 67 are disposed as close as possible to the reference portions 44 and 63. A lug 62' (FIG. 5) on sole 29 engages a vertical slot 47' disposed parallel to slot 47 in bar 43 to align the sole with respect to the cathode 39.

Since a typical tube of the present construction produces very high frequency oscillations at high power, such as on the order of 15,000 megacycles, at 100 watts of continuous power output, the high density beam may cause the very small interdigital line 61 to overheat. Referring to FIG. 12, fingers 72 of the interdigital line 61 are cooled and made stronger by providing an inner tapered portion 73 which is adjacent a support wall 74 of the slow-wave circuit 26 and which forms preferably one-half of the finger 72. The fingers 72 have an end portion 76 with a substantially uniform cross section, and a lower edge 77 of the end portion 76 is recessed inwardly of the lower surface of the interdigital line 61 and away from the electron beam to minimize electron interception. This arrangement of an inner taper portion 73 extending only to the midpoint of the finger 72 and an end portion 76 with a substantially uniform cross section provides minimum overlap between a finger 72 and an adjacent finger 72' to minimize capacitance between the two and produce high interaction impedance. The large cross section of the inner portion 73 near the side wall 74 improves cooling and strength.

The tube illustrated is a backward wave oscillator which converts the beam's kinetic energy to high frequency energy according to well-known physical principles. The high frequency wave is coupled out of the tube through

the waveguide 19 (FIG. 1). The waveguide 19 has a rectangular cross section with the side walls 74 which support the fingers 72 forming opposing walls of the waveguide. The first finger 72" (FIG. 8) in the interdigital line 61 extends into the waveguide 19 to form an elongated tapered fin 78 (FIGS. 1 and 2) which is disposed perpendicularly on one of the walls 74 of the waveguide to form the transition between the waveguide 19 and the interdigital line 61. In a backward wave oscillator, waveguide 21 may be used to feed back into the tube some of the energy extracted from waveguide 19. Waveguide 21 is constructed in a similar manner as waveguide 19 wherein tapered fin 78' forms the last finger 73''' of the interdigital line 61. Since the high frequency circuit comprising the waveguides 19 and 21 and the interdigital line 61 has two 90° bends, the inner surface 58' of the electrode 58 is tapered with a notch therein as shown to reduce reflections. A corner part 79 in waveguide 21 is constructed similar to the electrode 58.

Since the interdigital line 61 heats up considerably during operation, cooling water is circulated by tubes 81 and 82 into a vessel 83 which makes contact with side walls 74 (FIG. 4) of the interdigital line 61.

In the collector assembly at the end of the tube (FIGS. 1 and 3), the sole face fins 59 which fins substantially reduce secondary emission are continued on a sole extension plate 84 which is disposed in a recess 85 formed in the block 86 of collector assembly 28. Block 86 is bolted in place by suitably insulated bolts 86'. The sole extension plate 84 does not have side hats similar to the sole side hats 60. The recess 85 is much larger than the plate 84 so that a space is formed between the sides, the end, and the bottom of the plate 84 and the walls of the recess 85. The collector 28 has passages 88 which allow cooling water to circulate therethrough. The water is circulated by tubes 89 and 91 which extend out of the vacuum envelope. The insulator 93 and the ceramic bar 43 insulate the collector 28 from the body of the tube so that a depressed potential collector may be provided in the tube.

The electrons when they are emitted from the surface 55 of the cathode 39 are attracted by the anode 33 towards surface 54. The pole pieces 13 and 14 orient the magnetic field to cause the electrons to travel a cycloidal path and travel towards the space between the slow-wave circuit 26 and the sole 29. The cycloidal path of each electron varies since the electric field between the cathode and the anode varies, and the electric field can be so shaped to cause all the electrons to form cycloidal paths that will be closest to the anode at the edge of surface 54 which edge is near the slow-wave circuit 26. At this point the electric field strength is adjusted by sloping surfaces 57 and 57' to cause the electron to travel a path normal to the electric and magnetic field.

The side hats 56 on the cathode holder 38 and the side hats 60 on the sole prevent the beam from spreading laterally and retain the electrons close to the fingers 72 where the R.F. field is strongest.

After the electrons interact with the R.F. field they are collected by the collector. Since the beam current is relatively high and confined by the side hats 60 on the poles, the electrons in the beam must spread so that they can be collected over a large area to prevent overheating damage. Since the beam is traveling at a high velocity, considerable length is required before appreciable beam spreading is accomplished. To aid beam spreading the side hats 60 are removed from the sole after the interdigital line 61 terminates. The electric field between the plate 84 and collector housing is of a value which causes the beam electrons to turn around the end of the plate 84 and double back towards the electron gun so that they have time to spread before they are collected without increasing the length of the tube unnecessarily.

Referring to FIGS. 9 and 10 there is shown another embodiment of the present invention. A crossed-field

electron gun assembly 27' is shown which also produces a higher density beam than a gun of the prior art. The electron gun assembly 27' has an emitting surface 101 that has a gradient potential, that is, there is a potential difference between one end of the cathode with respect to the other end. A gradient cathode in this embodiment is formed, for example, by wire 102 such as thoriated-tungsten wound around three sapphire rods 103. The wire 102 is heated by a battery 104 that is polarized to make the end of the emitting surface 101 near the sole 29' negative with respect to the other end of the emitting surface 101. The sole 29' is biased negative with respect to the cathode by a battery 106, while the anode 107 which can be part of the slow-wave structure 26' is biased positive by battery 108. The equipotential electric field lines between the sole 29', the cathode surface 101 and the anode 107 are shown schematically in FIG. 11 by dotted lines 111 which will terminate on the cathode surface 101 as shown. The electrons emitted from the positive end of the surface 101 will follow a cycloidal path 112 and will not be recaptured by the cathode. Other electrons will follow other paths such as path 113. Thus, all the electrons emitted by the cathode will eventually form the electron beam and interact with the slow-wave structure.

A gradient cathode has an additional advantage in that by reversing the potential to the ends of the wire 102, the emissive current is interrupted or sharply decreased because almost all the electrons will return to the cathode. Then, if the potential of the D.C. power supply 104 is alternately reversed, the beam current will be modulated. In this type of application, the voltage of the D.C. power supply must be preferably lower than when the beam is unmodulated to prevent overheating of the cathode. Since the voltage of power supply 104 is low, somewhere between 25 v. and 100 v., the switching of potential can be done rapidly thereby reducing noise.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A high-frequency apparatus comprising an electron gun said gun being adapted and arranged to generate an electron beam, a slow-wave structure, and a collector, said slow-wave structure comprising an interdigital line including a plurality of fingers mounted on spaced parallel support walls, said fingers being interdigitated, adjacent fingers being affixed to opposite walls at the one end of said fingers and free at the other end thereof and said fingers being tapered along the length thereof, said taper being such that the cross-section of said fingers is considerably reduced at the mid-portion of the length thereof relative to cross section at the fixed end thereof, said fingers having a relatively minute change in cross section from approximately said mid-portion thereof to said free end thereof.

2. The high-frequency apparatus of claim 1 wherein the apparatus as defined in claim 1 wherein said fingers are tapered from said mid-portion to said free end such that a relatively minute change in cross-section from approximately said mid-portion of said fingers to said free end of said fingers results, said taper from said mid-portion to said free end being dimensionally located on said fingers such that electron beam interception by said fingers is reduced.

3. A crossed-field high-frequency apparatus comprising an electron gun, a slow-wave circuit, and a collector, said electron gun having a cathode with a planar emitting surface facing an anode having a planar anode surface, said planar anode and said planar cathode surfaces each having an edge located near said slow wave circuit and

each having an opposite edge spaced further from said slow wave circuit than said near edge and wherein the distance between said planar anode surface and said planar cathode surface at the edge of said cathode near said slow-wave circuit is smaller than the distance between said planar anode surface and said planar cathode surface at the opposite edge of said cathode, the electric field strength established between said cathode planar emitting surface and said anode planar surface increasing from the upstream to the downstream edges of said cathode planar emitting surface such that electrons emitted from said cathode planar emitting surface are accelerated into an electric field of increasing electric field strength between the upstream and downstream end portions of said gun.

4. A crossed-field high-frequency apparatus comprising an electron gun, a slow-wave circuit, and a collector, said electron gun having a gradient cathode electron emission surface having a near end edge thereof positioned near said slow wave structure and a far end edge thereof spaced further from said slow wave structure than said near end edge and wherein the end edge of the cathode near the slow-wave structure is at a negative potential with respect to the other end edge of the cathode.

5. A crossed-field high-frequency apparatus comprising an electron gun, a slow-wave circuit, and a collector, said electron gun having a cathode having a generally planar emission surface facing an anode having a generally planar surface said anode and cathode forming a wedge-shaped chamber such that a non-uniform electrostatic field is formed therebetween, said non-uniform electrostatic field formed between said anode and cathode increasing from the upstream end of said cathode to the downstream end of said cathode.

6. A crossed-field high-frequency apparatus comprising an electron gun, a slow-wave structure, and a collector, said electron gun having an anode spaced from a cathode, said cathode comprising insulating means and an electron emission heating wire wound around said insulating means wherein a planar surface is formed by the wire which is disposed adjacent said anode to form an electron emitting surface.

7. A crossed-field tube comprising an electron gun for forming and directing an electron beam along a beam path, a slow wave circuit disposed parallel to said beam path, a sole electrode disposed parallel to said beam path and on the opposite side thereof from said slow wave circuit, a collector, and means for maintaining an accurate spacing between said slow wave circuit and said sole electrode, and wherein said means comprises a ledge on said slow-wave circuit accurately positioned from the interaction means on said slow-wave circuit; a protruding ridge on said sole electrode; a ceramic bar having a groove accurately disposed from an edge, along the length thereof said edge being disposed against said ledge and said protruding ridge being disposed within said groove; and second means for urging said sole towards said slow-wave structure whereby said ridge bears against said groove and said edge in turn bears against said ledge.

8. A crossed-field tube comprising an electron gun for forming and directing an electron beam along a predetermined electron beam path, a slow-wave circuit disposed parallel to said beam path on one side of said beam path, a sole electrode disposed parallel to said beam path and on the opposite side thereof from said slow-wave circuit, and a collector, said slow-wave circuit including two side walls having an interdigital line formed along their edge that is disposed adjacent said sole, means on said sole for retaining the electrons in the beam close to the said interdigital line, said means comprising side hats disposed on each side of said sole along the length of said sole, said side hats being disposed closer to said slow wave circuit than any other part of said sole, said sole and said slow wave circuit extending along said predetermined electron beam path between said elec-

tron gun and said collector, the spacing between said sole and said slow wave circuit being tapered from a larger spacing therebetween at the electron gun end of said sole and said slow wave circuit to a relatively smaller spacing therebetween at a distance along said sole and said slow wave circuit removed from said electron gun end.

9. A crossed-field tube comprising an electron gun for forming and directing an electron beam along a predetermined electron beam path, a slow-wave circuit disposed parallel to said beam path, a sole electrode having a pair of side hats disposed along a portion of the length thereof disposed parallel to said beam and on the opposite side thereof from said slow-wave circuit and a collector, said collector being disposed at the end of said sole opposite said gun, said collector spaced from the sides, end and bottom of said sole, and means for causing the electron beam to turn around the end of said sole and continue between said sole and said collector until the beam spreads sufficiently to be collected, said sole electrode having the side hats removed in the vicinity of said collector region.

10. A crossed-field tube comprising an electron gun for forming and directing an electron beam along a predetermined electron beam path, a slow-wave circuit disposed parallel to said beam path, a sole electrode disposed parallel to said beam and on the opposite side thereof from said slow-wave circuit, a collector, and first means for maintaining an accurate spacing between said slow-wave circuit and said sole, said slow-wave circuit comprising an interdigital line including a plurality of fingers mounted on two parallel support walls, said fingers being tapered and fixed by the larger cross section thereof to each of the support walls, said electron gun having a cathode with an emitting surface facing an anode surface and forming a non-uniform electrostatic field therebetween, said collector being disposed at the end of said sole opposite said gun, and spaced from the side, end and bottom of said sole, and second means for causing the electron beam to turn around the end of said sole and continue between said sole and said collector until the beam spreads sufficiently to be collected.

11. The crossed-field tube of claim 10 wherein said first means comprises a ledge on said slow-wave circuit accurately positioned from the interaction means on said slow-wave circuit; a protruding ridge on said sole electrode; a ceramic bar having a groove accurately disposed from an edge thereof, said edge being disposed against said ledge and said protruding ridge being disposed within said groove; and third means for urging said sole towards said slow-wave circuit whereby said ridge bears against said groove and said edge in turn bears against said ledge.

12. A crossed-field tube comprising an electron gun for forming an electron beam, a slow-wave circuit disposed parallel to said beam, a sole electrode disposed parallel to said beam on the opposite side thereof from said slow-wave structure, said sole electrode having side hats disposed thereon along a portion of the length thereof, a collector, and first means for maintaining an accurate spacing between said slow-wave circuit and said sole, said collector being disposed at the end of said sole opposite said gun, said collector spaced from the sides, end and bottom of said sole, and second means for causing the electron beam to turn around the end of the sole and continue between said sole and said collector until the beam spreads sufficiently to be collected, said sole electrode having the side hats removed in the vicinity of said collector.

13. A crossed-field tube comprising an electron gun for forming an electron beam, a slow-wave circuit disposed parallel to said beam, a sole electrode disposed parallel to said beam on the opposite side thereof from said slow-wave circuit, a collector, and first means for maintaining an accurate spacing between said circuit and said sole, said slow-wave circuit comprising an interdigital line including a plurality of fingers mounted on parallel support walls, said fingers being tapered and fixed by the

larger cross section thereof to the support wall, said electron gun having a cathode with an emitting surface whose length in the direction of beam travel is greater than the length of a cycloidal period followed by any electron emitted by the emitting surface and the crest of the cycloidal period followed by the same electron, said collector being disposed at the end of said sole opposite said gun, said collector being disposed opposite a portion of each of three sides of said sole and at its end, second means for causing the electron beam to turn around the end of the sole and continue between said sole and collector until the beam spreads sufficiently to be collected, and coupling means for coupling high frequency energy with said slow-wave structure.

14. The crossed-field tube of claim 13 wherein said first means comprises a ledge on said slow-wave structure accurately positioned from the interaction means on said slow-wave structure, a protruding ridge on said sole electrode, a ceramic bar having a groove accurately disposed from an edge, said edge being disposed against said ledge, said protruding ridge being disposed within said groove, and third means for urging said sole towards said slow-wave structure whereby said ridge bears against said groove and said edge in turn bears against said ledge, said electron gun having a cathode with a planar emitting surface facing a planar anode surface, and the distance between the surfaces at the edge near the slow-wave structure is smaller than the distance between the surfaces at the opposite edge thereof.

15. The crossed-field tube of claim 13 wherein said first means comprises a ledge on said slow-wave structure accurately positioned from the interaction means on said slow-wave structure, a protruding ridge on said sole electrode, a ceramic bar having a groove accurately disposed from an edge, said edge being disposed against said ledge, said protruding ridge being disposed within said groove, and third means for urging said sole towards said slow-wave structure whereby said ridge bears against said groove and said edge in turn bears against said ledge, said electron gun having a cathode with a planar emitting surface facing a planar anode surface, and the distance between the surfaces at the edge near the slow-wave structure is smaller than the distance between the surfaces at the opposite edge thereof.

16. A high frequency apparatus comprising, an electron gun, for generating and directing an electron beam along a predetermined electron beam path, a slow wave circuit, and a collector structure, said slow wave circuit comprising an interdigital structure including a pair of spaced substantially parallel support walls wherein one of said parallel support walls has a first plurality of fingers affixed thereto, each of said first plurality of fingers being directed along the length dimension thereof towards and spaced from the other of said parallel support walls, said first plurality of fingers being spaced from said electron beam path, said fingers defining a side thereof furthest removed from said electron beam path and said fingers defining a side thereof closest to said electron beam path,

said first plurality of fingers defining a first plurality of spaced parallel planes, said first plurality of spaced parallel planes being substantially perpendicular to each of said spaced parallel support walls, and wherein the other of said parallel support walls has a second plurality of fingers affixed thereto, each of said second plurality of fingers being directed along the length dimension thereof towards and spaced from the one of said parallel support walls, said second plurality of fingers being spaced from said electron beam path, said fingers defining a side thereof furthest removed from said electron beam path and said fingers defining a side thereof closest to said electron beam path, said second plurality of fingers defining a second plurality of spaced parallel planes, said second plurality of spaced parallel planes being substantially perpendicular to each of said spaced parallel support walls, said first plurality of spaced parallel planes being interdigitated with respect to said second plurality of spaced parallel planes, said fingers having an enlarged cross-section at the portion affixed to said supported wall and said fingers being tapered over a portion of the length thereof such that a substantially reduced cross section exists in the vicinity of the midportion of the fingers taken along the length thereof, said fingers being substantially non-tapered from said mid portion to said free end along the side thereof furthest from the electron beam path.

17. The device as defined in claim 16 wherein said fingers have the side closest to the electron beam path tapered away from said beam path thereby decreasing electron interception by said interdigitated slow wave structure.

18. A crossed-field high frequency electron discharge gun, said electron discharge gun comprising a cathode with an electron emission surface, said emission surface having upstream and downstream end portions aligned along the direction of electron flow from said emission surface and means for establishing a potential gradient along the emission surface of said cathode between said upstream and downstream end portions of said emission surface, said gun further including means for establishing crossed-electric and magnetic fields in said gun region.
